UNITED STATES PATENT OFFICE.

HENRY LA CASSE, OF SYRACUSE, ASSIGNOR TO SOL WILE, OF ROCHESTER,
NEW YORK.

MACHINE FOR CORKING AND WIRING CORKS TO BOTTLES.

SPECIFICATION forming part of Letters Patent No. 400,776, dated April 2, 1889.

Application filed July 30, 1888. Serial No. 281,381. (No model.)

To all whom it may concern:

Be it known that I, HENRY LA CASSE, of Syracuse, in the county of Onondaga, in the State of New York, have invented new and useful Improvements in Machines for Corking and Wiring Corks to Bottles, of which the following, taken in connection with the accompanying drawings, is a full, clear, and exact description.

10 My invention relates to improvements in machines for bottling liquids, and has for its object the production of a machine containing novel mechanism for corking the bottles and wiring the corks securely thereto, the wire being first secured to the cork and then passed around the neck of the bottle and over the top of the cork, in such manner that when it is desired to open the bottle the wire may be untwisted from the neck of the bottle and 15 utilized as a means for drawing the cork from the bottle.

In all wiring and corking machines heretofore used no means were provided for drawing the cork aside from the use of a cork-screw; hence the difficulty in withdrawing the cork has led to the introduction of numerous patented bottle-stoppers made of rubber and other materials which were detrimental for use in bottling fine beverages, 20 and these patented stoppers, while much easier to manipulate in drawing them, have failed to meet the popular favor for use on fine bottled beverages, for the reason that the rubber used to make the stopper tight was 25 apt to taste or deteriorate the quality of the beverage. My invention is designed to obviate these objections by utilizing the ordinary cork stopper provided with a wire pull, which is formed of the wire used to wire the cork to the bottle when the bottles are corked; and to 30 this end my invention consists, essentially, in a machine wherein the wire is automatically applied to the cork by suitable mechanism and the cork with the wire secured thereto 35 forced into the bottle, of mechanism for securing the wire to the neck of the bottle and over the top of the cork, and mechanism for cutting off the wire from the wire-reel, all of the said operations being performed automatically after the bottle is placed into the 40 machine and motion communicated to the

mechanism from the prime motor, all as hereinafter fully described, and pointed out in the claims.

In specifying my invention reference is had 55 to the accompanying drawings, forming a part of this specification, in which like letters indicate corresponding parts in all the views.

Figure 1 is a top plan of a machine containing my invention, illustrating the mechanism in position to operate when a bottle is placed in the machine, the wire-carrying device and its actuating mechanism being shown ready to start forward and carry the wire around the cork of the bottle, also 60 illustrating the mechanism and timing devices which automatically bring into operation the different parts of the machine essential to carry out the various steps in the operation of corking and wiring the bottle. 65 Fig. 2 is a front elevation of a machine containing my invention, illustrating the bottle in position to be operated on by the wiring and corking mechanism, the wire-carrying device being shown as advancing forward, 70 bringing the wire in position to encircle the cork when the cork is placed in the compressor-tube. This view also illustrates the construction and arrangement of the mechanism for allowing the wire-carrier to oscillate, so that the same may raise or lower automatically in applying the wire to the neck of the bottle after the cork is forced home. 75 It also illustrates the mechanism for rotating the bottle, thereby twisting the wire over the 80 top of the cork. Fig. 3 is an elevation of the opposite or rear side of a machine containing my invention, illustrating the main shaft and its connecting mechanism for transmitting motion to the wire-carrying mechanism, and 85 also to the compressor and plunger for forcing the cork home into the bottle. It also illustrates the pedal for throwing the machine into action through the medium of a clutch engaging with the pulley of the prime motor. 90 Fig. 4 is an end elevation from the right of a machine containing my invention, illustrating further details of construction of the various parts shown in the preceding views, and 95 illustrating more particularly the cork-compressor and its actuating means, the bottle to be operated on being shown embraced by 100

arms which serve at the proper time to lift the wire up over the top of the cork when the cork is forced home into the bottle. Fig. 5 is a like view enlarged and showing the compressor partly in section, illustrating more particularly the detail construction and operation of the compressor upon the cork, which is shown inclosed therein, also illustrating the contour and arrangement of the cams which actuate the cork-compressor and the plunger for forcing the cork home into the bottle, the mechanism for operating the compressor being illustrated as at the commencement of its movement in the operation of compressing the cork. Fig. 6 is a like enlarged view illustrating the same parts, but showing the compressor forced home on the cork and the plunger for forcing the cork into the bottle starting its movement for that purpose. Fig. 7 is a like enlarged view illustrating the compressor mechanism locked out of the path of its actuating-cam and the plunger forcing the cork into the bottle, the cork momentarily stopped in its downward passage at the point, as shown in the illustration, to allow the wire-carrier and shuttle to cause the wire to encircle it and to secure the wire thereto in order to utilize the wire as a pull to remove the cork. Fig. 8 is an enlarged front side elevation, partly in section, illustrating the wire-carrying devices and shuttle at the moment of the commencement of the rearward movement of the wire-carrier, leaving the wire secured to the cork, while the cork is just started into the neck of the bottle, as shown in Fig. 7, the neck of the bottle being broken away for the purpose of illustration. Fig. 9 is an enlarged front side elevation similar to Fig. 8, showing the wire-carrier and shuttle as having twisted the wire the proper length to permit the wire to extend over the top of the cork and encircle the neck of the bottle. Fig. 10 is a like view illustrating the wire-carrier and shuttle again starting forward, so as to carry the wire to the other side of the neck of the bottle, and illustrating the cork forced home by the plunger. Fig. 11 shows an enlarged end elevation of the machine, taken from the same end as shown in Figs. 4, 5, and 6, illustrating the means secured to the plunger-shaft for releasing the compressor when the cork is forced home into the bottle and the position of the cam which actuates the walking-beam for forcing down the plunger. Fig. 12 is an enlarged side view of the mechanism for laying the projecting end of the twisted wire over the top of the cork after the same is forced home into the bottle, illustrating also the detail construction and arrangement of the cam and its timing devices for regulating the movement of the actuating mechanism. Fig. 13 is a top plan view of the mechanism illustrated in Fig. 12. Fig. 14 is an enlarged detached side elevation of the wire-carrier, shuttle, and its actuating mechanism, showing the shuttle dropped

down to carry the wire over the top of the cork and neck of the bottle preparatory to encircling the neck therewith. Fig. 15 illustrates a like view showing the wire-carrier 70 and shuttle elevated to its normal position and retracted to carry the wire around the neck of the bottle and to the other side thereof preparatory to the finishing operation. Fig. 16 is a like view illustrating the operation of the swiveled jaws which carry the projecting end of the wire shown in Fig. 15 upward and above the top of the cork in the finishing step of the operation, also illustrating the mechanism for turning the bottle, 80 which twists the ends of the wire onto the top of the cork, thereby securing it ready for the stroke of the cut-off mechanism which severs the wire from the shuttle. Fig. 17 is an enlarged side view of the mechanism for 85 cutting off the wire after the operation of twisting the same on the cork has been completed. Fig. 18 is an enlarged longitudinal vertical section taken on line xx of Fig. 1, showing the driving-pulley, its clutch, the cams 90 for operating the plunger and compressor, and the clutch for bringing the cams into action, and illustrating the detail construction and arrangement of the various parts mentioned. Fig. 19 is an enlarged longitudinal vertical section taken on line yy of Fig. 1, illustrating the cams for operating the clutch on the main shaft which rotates the wire-carrier and shuttle, and also the cam which actuates the clutch mechanism illustrated in Fig. 18 for 95 throwing the compressor and plunger cams into action; and Fig. 20 is a transverse vertical section taken on line zz of Fig. 1, illustrating the detail construction and arrangement of the pivoted shafts which transmit 100 motion to the wire-carrier and its shuttle and the gears for rotating the wire-carrier in order to twist the wire after the wire has encircled the cork and the neck of the bottle, and it also illustrates the cord and weight for 105 compelling the wire-carrier and shuttle to follow the travel of its actuating-cam, thereby retracting the wire-carrier at the proper time. In describing this the preferred example of my invention, I have divided the mechanism into various steps in order to facilitate the description thereof, and have designated the parts relating to each step as follows, viz: first, the feeding devices for feeding forward the wire over the bottle; second, the compressor mechanism which compresses the cork and prepares the same for the mechanism which forces the cork home; third, the plunger and its operating mechanism which serves to force the cork into the bottle; fourth, the mechanism for carrying the wire over the top of the bottle and the cork, and, fifth, the cut-off mechanism for cutting off the wire and finishing the operation of corking and wiring the bottle. 115

A represents the main frame of the machine, mounted on suitable supports or legs,

A', said frame being of any desirable form and dimensions and made of any suitable material.

5 B B are uprights rising from the top of the frame, supporting the main shaft and the plunger and compressor mechanism.

C is the main shaft, journaled in bearings secured in the upright B at one end and the upright B² at its opposite end.

10 D is the belt-pulley which transmits motion from the prime motor to the main shaft.

E is a worm on the main shaft C, which meshes with a worm-gear, E', on the shaft F and serves to transmit motion to the cross-shaft F, which in turn transmits motion to the wire carrier and shuttle.

15 G is a gear on the main shaft, which meshes with a gear, G', on the cross-shaft H and serves to transmit motion to the shaft H and 20 rotates the wire-carrier and shuttle, the said rotation serving to twist the wire, as will be explained farther on.

25 I is the wire-carrier, which consists of the wire-reels and shuttles, serving to supply necessary wire in the operation of wiring the corks to the bottles.

J is the bottle-support, secured to the frame A underneath and in line with the plunger P, as best shown in Fig. 2.

30 K is a rack engaging a pinion on the spindle of the bottle-support J, and serves to revolve the bottle at the proper time to secure the wire to the top of the cork.

35 L, Fig. 2, is the lever which operates the rack K to revolve the bottle.

M M are jaws which embrace the neck of the bottle, holding it firmly, and serving at the proper time to force the wire upward over the top of the cork.

40 N is a hammer which serves to cut off the wire from the shuttle in the finishing step of the operation.

45 O is a clutch on the main shaft C, which is actuated to engage the pulley D, and thereby start the machine, it being understood that the pulley D, connected to the prime motor, is constantly in motion, turning loosely on the shaft C until the clutch O is thrown into engagement with the hub of the pulley by pressing down on the pedal Q, which movement is 50 transmitted to the clutch O through the medium of the pivoted lever R.

P is the plunger, which forces the cork home through the compressor-support S.

55 S' is the compressor, in which the corks are inserted and compressed by the compressor mechanism.

T is a table or stand connected to the machine, and serves as a convenient support for 60 bottles which are to be corked and wired in the machine.

U is the hanger which supports the shaft for operating the wire-carrier.

65 V is the lever for oscillating the hanger which carries the journal of the wire-carrier, thereby lowering and raising the wire-carrier in its different operating positions.

W is the walking-beam, carrying the plunger P, which forces the cork home into the bottle.

70 The wire carrying and feeding devices consist, essentially, of the carrier I, which consists of a frame supporting two reels, r r, or spools of wire and two spring-tensioned shuttle-jaws, a a, Fig. 1, pivoted to lugs projecting outwardly from the frames of the reels r r.

The shuttle-jaws a a are tensioned or forced toward each other by means of the spirals a', Fig. 1. The wire-carrier I is secured to the shaft b by means of the set-screw b', which 80 passes through the hub I' of the carrier-frame. The shuttle-jaws a terminate in rounded knobs a² and oscillate or swing outwardly away from each other on their pivots, for a purpose presently explained. The carrier I 85 has a rectilineal movement toward and from the bottle-support J, and it also oscillates on the shaft F as a pivot, for the purpose of permitting the carrier to lower or raise when the wire is placed around the neck of the bottle 90 and drawn up over the top of the cork. The forward and rearward movement of the carrier is secured by mounting the shaft b in the hanger U, so as to allow it to move endwise 95 therein.

The shaft b of the carrier is supported near its forward end in the free extremity of the hanger U, which is provided with the sliding bearing c, mounted in the slot c' in the post X, Figs. 1 and 9, which rises from the frame A of the machine. The opposite or rear end of the shaft b is supported in the bearing d' of the hanger U and the independent bearing d, adapted to slide rectilineally in the hanger U, and provided with the frictional roller e, 100 which, as shown in Figs. 1 and 8, is held constantly in contact with the cam i, mounted on the shaft F, by means of the weight Y, secured to the cord 3, passing over the grooved pulley 2, and fastened to the bearing d by a 105 screw, 4. The bearing d of the shaft b is guided in its rectilineal movement on rods f f', which pass through the hub U' and the projecting bearing d' of the hanger U.

110 It will be observed that the hanger U is made integral with the hub U' and the bearing d', and the forward ends of the rods f f' are secured to the bearing d' by set-screws f² f³, while the rear ends of the rods f f' are secured to the hub U' by set-screws 5 6.

115 The end of the shaft b is turned down or reduced in diameter at b², so as to provide a shoulder which bears against the forward end of the sliding bearing d, while a collar, e', secured to the end of the shaft, securely connects the shaft b to the sliding bearing d. The hanger U, with its projecting hub U', journaled on the shaft F, serves to allow the 120 oscillating movement of the wire-carrier I, as previously described, and the oscillation of the wire-carrier is secured by means of the rocking lever V, Figs. 1 and 2, which is actuated by the cam h on the shaft F, as best 125 shown in Fig. 2.

The rocking lever V is provided on the end which contacts with the cam h with the friction-roller V', while its opposite end, V², is concaved and supports the elbow-bearing Z' 5 from underneath, as best shown in Figs. 2 and 15.

It will be observed that as the shaft F rotates the cam h, riding against the friction-roller in the end V' of the rocking lever V, carries the end V' of the lever down, and thereby raises the wire-carrier as the large part of the cam passes over the friction-roller, while the wire-carrier is lowered when the small portion of the cam is in contact with the friction-15 roller in the end V'. The bearing c, which rests in the slot c' of the upright X, is formed integral with the hanger U and is allowed a vertical movement in the said upright X in its slot c', while the gear g' has a rectilineal 20 movement on the shaft b on the spline g², the spline g² being secured to the gear and sliding in a longitudinal groove in the shaft b. The shaft H, upon which the gear g, which meshes with the gear g', is journaled, is journaled in 25 the elbow-bearing Z', as shown in the top plan view, Fig. 1, and necessarily follows the oscillating movement of the shaft b, and to allow this movement the shaft H is provided back of the gear g with a bearing or sleeve, o, 30 which has a vertical movement in the slot n of the post X', Fig. 20, and is provided with a tapering shoulder, 47, which bears against the two-part face n' of the post X', and serves to keep the gears g g' in mesh during the oscillation of the shafts b and H. The position of the wire-carrier I in its first movement forward is shown in Fig. 2.

It will be observed upon reference to Figs. 8, 9, and 10 that the cam i, which impels the wire-carrier forward, is two-winged, the wings being so timed that as the cam rotates the carrier is impelled forward from the point of the wing, and the first forward movement of the carrier is so timed in relation to the movement of the plunger, which forces the cork down, that the shuttle-jaws are carried over the neck of the bottle, so that the cork may be forced down between the two shuttle-jaws of the carrier. The cork at this point entering the neck of the bottle about a quarter of an inch, the carrier and jaws are immediately retracted by the travel of the cam and the force of the weight Y on the bearing d, and as soon as the rearward movement of the carrier 45 commences the shaft H commences to rotate by mechanism which throws it into gear, which will be presently explained, and secures the twisting motion of the carrier, which serves to twist the wire on the cork, thereby securing 50 the wire to the cork. The rearward movement of the carrier is so timed that a sufficient length of wire is twisted that when the cork is driven home into the bottle, carrying the wire with it, the remaining wire is sufficient to extend over the top of the cork and 55 around the neck of the bottle. As soon as the cork is forced home into the bottle, the wire-

carrier again moves forward, and this time the cam h is rotated, so as to bring the smaller portion thereof in contact with the end V' of the rocking lever V, which allows the shuttle-jaws to drop with the oscillation of the shaft b, so that the shuttle-jaws a encircle the neck, as shown in Fig. 14. This movement of the shuttle-jaws brings the wire w over the top 70 of the cork and down around the neck of the bottle. The rearward movement of the wire-carrier pulls the wire taut, and the wire-carrier again resumes its normal position in a horizontal plane by the further travel of the cam h against the friction-roller in the end V' of the lever V. As the carrier moves rearward, the twisting motion is again resumed and the wire twisted, as shown in Fig. 15. At the next advance of the wire-carrier the final 80 step in the operation takes place, which secures the wire w to the top of the cork, and the wire is cut off by mechanism which will be presently described.

The rotation of the wire-carrier I is accomplished by the shaft H and its gears g g', the said shaft H being rotated by the gear G on the main shaft C, which meshes with the gear G' of the shaft H. The end of the shaft H bearing the gear G' is journaled in the T-95 box Z, Fig. 1, and is driven by the gear G, which is loosely mounted on the shaft C and actuated at the proper time by means of a clutch, p', Figs. 3 and 19. The clutch consists of a loose section carried by the hub of the 100 gear G and a sliding section provided with a spline which moves in a longitudinal groove in the shaft C. The sliding section of the clutch is operated by the clutch-dog 11, secured to the shaft m, which is mounted in the 105 U-bearing C³, Figs. 3 and 19, and is actuated by the engagement of the cam m² with the end m' of the shaft m. A spiral, 12, serves to 110 retract the sliding section of the clutch after the cam m² has passed the end m' of the shaft.

It will be observed that the wire-carrier I is rotated as it moves backward, and that it moves rearward twice in performing its office. Consequently I construct the cam m² in two parts, as best shown in Fig. 19, the said cam being shown as formed on a three armed wheel, and having the cams substantially opposite to each other and of suitable length to allow the necessary length of wire to be twisted for the steps of the operation, the 115 arms 48, 49, and 50 being connected to the rim of the cam adjustably by means of set-screws p, passing through the slots l⁴ in the rim, which permits sufficient adjustment to time the travel of the cams to secure the desired result. Motion is communicated to the shaft F, upon which the cam m² is mounted, by means of the worm E, which meshes with the worm-gear E'.

The rounded ends of the shuttle a are provided for the purpose of obviating friction as the shuttle-jaws are forced apart when the wire-carrier moves rearward in the operation of placing the wire around the neck of the 130

bottle, and the necessary tension of the wire on the reel is secured by taking a turn or two around the shuttle-jaws with the wire *w*, as best shown in the plan view, Fig. 1.

5 It will be observed upon reference to Fig. 1 that the normal position of the wire-carrier *I* is with the jaws standing in a horizontal plane, and it is necessary that the rotation of the shaft *b* shall be so timed as to leave the wire-carrier in its normal position at the commencement of each forward movement, for the reason that the shuttle-jaws *a* must be in position to embrace or encircle either the cork or the neck of the bottle, and to secure 10 this position of the wire-carrier at the termination of its rotating movement I provide the following mechanism, which is best shown in Figs. 3, 19, and 20, Fig. 3 showing a side elevation thereof.

20 In a forked bearing, *A*², I pivot the lever *F'*, said lever being provided with the forked stud *F*², which guides the pawl-lever *H'*, which is also pivoted to the forked bearing *A*². The lever *H'* is provided with a stud, 15, 25 which takes in the notch 14 of the gear *G*, while the spring 51 forces the pivoted lever *H'* with a constant pressure toward the gear *G*. The pawl-hook 15 is prevented from engaging with the notches 14 in the gear by reason of its contact with the lever *F'*, which is 30 timed by means of the sliding section of the clutch *p'*. The upper end of the lever *F'* is provided with an angular stud bearing a friction-roller, which rides in the groove 13 of the sliding section of the clutch, and when 35 the clutch is operated to cause the rotation of the shaft the shoulder 53 in the projecting forked bearing presses the pawl-lever *H'* away from the gear *G*, and consequently disengages 40 the pawl-hook 15 from the gear, and as the sliding section of the clutch is retracted the spring 51 forces the lever *H'* inward, so that the pawl-hook 15 engages the notch in the gear.

45 In order to make certain of stopping the rotation of the carrier *I* at the right place every time, I prefer to employ two stopping-points, and consequently provide two notches, 14, in the gear *G* at the right point to stop the carrier in its normal position.

50 The compressor *S'* is supported on the bracket *S*, projecting from one of the uprights *B*, mounted on the frame *A*, and is composed of two parts, one of which is semi-tubular in form and provided with the bulb or swell 53 near its exit. The other portion is hinged at 26 to the semi-tubular portion, and serves to squeeze or compress the cork when it is rocked on its pivot by means of the rod 55 *s*, which is hinged at 21 to the swinging jaw of the compressor. The swinging jaw of the compressor is segmental in shape, and forms one segment corresponding in contour interiorly to the semi-tubular portion thereof. The bracket or support *S* is provided with a curvilinear slot, 29, and the hinge-pin 21 is 60 extended on both sides of the support and

provided with friction-rollers 30, which ride in the curvilinear slot 29 and guide the movement of the compressor-rod *s*. 70

In order to secure the compressor in a fixed position at the time the cork is forced through the compressor into the neck of the bottle, I provide the hinged lever *K'*, Fig. 11, pivoted to the bracket or compressor-support *S*, and 75 having a hook, 28, which takes over the projecting hinge-pin 21 of the compressor-rod *s*. The hook-lever *K'* is provided with a projection, 27, on its opposite end, which lies in the path of the rod *P'*, carried in the collar *P*², 80 secured to the plunger *P*. The compressor *S'* is operated by the cam *u*, mounted on the shaft *C* between the uprights *B*, as best shown in Fig. 3, and the compressor-rod *s* is provided with a friction-roller, *s'*, in its end, and 85 the said cam *u*, bearing against the friction-roller *s'*, serves to force the compressor against the cork. The compressor-rod *s* is supported in proper position to contact with the cam *u* by the upright *A*³, which is provided with the 90 rocking bearing *A*⁴, through which the rod *s* passes. A spiral, 18, bearing against the collar and set-screw 19, serves to tension the rod *s* to retract the rod and release the compressor when the hook-lever *K'* is tripped by the 95 depending-finger *P'*, operated by the descent of the plunger *P*.

At Fig. 5 I have illustrated the position of the plunger when the cork is inserted in the compressor. It will be observed that the cork 100 is dropped in the compressor as the hinged segment of the compressor lies open at the top in the position shown in the figure. When motion is communicated to the main shaft *C* by means of the clutch *O* and the shaft rotates, the impingement of the cam *u* on the friction-roller *s'* impels the compressor forward against the cork and presses the cork to a suitable size or perhaps a little smaller than is necessary to freely enter and close the 105 bottle, and at the same time that the hinged section of the compressor presses the cork the compressor is forced downward until the mouth of the compressor comes in close proximity to the top of the bottle, and the compressor then constitutes a guide to guide the cork into the mouth of the bottle, when the cork is forced down by the plunger, as shown in Fig. 6. The bulb 52 allows the cork to 110 swell slightly after being compressed to relieve any creases which may have been formed in the cork in the compressing operation.

The oscillation of the rod *s* of the compressor is allowed by providing the slot 20 in the upright *B*, through which the shaft *s* passes. The 115 plunger *P* passes through brackets 22 and *P*³, the said brackets being provided with the guideways 23 and *P*⁴. The plunger is connected by the pivoted bearing *W*³ to the walking-beam *W*, which is pivoted in a bearing, 120 *W'*, on the cross-piece or yoke *B'*, mounted on the uprights *B* *B*. The walking-beam is actuated by the cam *t*, mounted on the shaft *C*. The cam *t* bears against the friction-roller *t'*, 125

journalized in the end of the rod l^2 , which passes through the guide-bearing t^3 , secured to the upright B , and the rod l^2 is connected to the walking-beam W by the pivoted bearing W^2 , 5 and the friction-roller t' is kept in contact with the cam t by means of the rod 31 and spring 37, connected thereto, as best shown in Fig. 4. It will be observed upon reference to Figs. 5, 6, 7, and 11 that the cam t as it rotates in 10 contact with the friction-roller t' is so timed in relation to the operation of the compressor that the stroke of the plunger on the cork is started after the cork is compressed, and then after the cork is forced into the bottle the extent of, say, one-quarter of an inch the further movement of the plunger is arrested momentarily to permit the wire-carrier and its 15 shuttle to secure the wire to the cork, when the further travel of the cam u forces the plunger down, carrying with it the cork, and the downward movement of the plunger P carries with it the finger P' , secured to the collar P^2 , as shown in the views referred to, and the collision of the finger P' with the 20 hook-lever K' throws up the hook 28 off of the hinge pin 21, thereby releasing the compressor, which is retracted back to its normal position by the spiral 18 on the rod s , resetting the compressor for a subsequent operation 25 while the remaining steps in corking the bottle and wiring the cork thereto are taking place.

The cams t u , which serve to operate the plunger and compressor, are loosely mounted 30 on the shaft C , as best shown in the sectional view, Fig. 18, and are brought into operation at the proper time by means of the cams t^2 t^2 , projecting from the same wheel which carries the cams m^2 m^2 on the shaft F . The cams t^2 t^2 35 collide with the friction-roller t' , which is secured in the end of the rod l , supported in the bearings C' C^2 , Fig. 3, said rod l carrying the clutch-dog 7, which rides in the groove 8 of the sliding clutch-section of the clutch p , 40 engaging the cams t u .

It will be observed upon reference to Fig. 18 that the sliding section of the clutch p is provided with the spline 25, which takes in a longitudinal groove in the shaft C , so as to 45 slide freely therein, and that the forward movement of the rod l carries the sliding section of the clutch into engagement with the clutch-section formed on the hub of the cam. A spiral, 9, bearing against the bearing C' and 50 the collar 24, serves to throw the clutch p out of engagement at the proper time to stop the cams t u . After the cork has been forced into the bottle by the plunger P the end w of the wire is laid over the top of the bottle by 55 means of the hammer N , which is provided with a spring-shank, N' , connected to a pinion, N^2 , so as to turn inward when the pinion is rotated on its pivot. The rotation of the pinion N^2 is accomplished by the rack N^3 , 60 which is operated automatically by the cam k , which impinges the pivoted lever k' , motion being transmitted to the rack by the rod k^2 .

The cam k is provided with notches 39 and 40, and the pivoted lever k' is provided with a stud, 38, which is held normally against the 70 periphery of the cam k by means of a spiral, 41. When the stud 38 of the lever k' is in contact with the periphery of the cam k , the hammer N is in the position shown by the full lines in Fig. 1 and the dotted lines in Fig. 13. 75 When the notches 39 and 40 come around to the stud 38, the spring 41 forces the stud into the notch, thereby oscillating the lever outward, carrying with it the rod k^2 , which in turn transmits motion to the rack N^3 , rotating 80 the pinion N^2 and causing the hammer N to move inward quickly, and thereby lay the projecting end of the wire w over the top of the cork. The stud 38 is immediately released from the notch 39 by the continued rotation of the cam k , which forces the lever k' 85 forward, returning the hammer N to its normal position.

The mechanism in its various positions while accomplishing the laying of the wire 90 over the cork is illustrated in Figs. 12 and 13. It will be observed upon reference to the dotted lines in Fig. 12 that the shuttle of the wire-carrier I is just clear of the neck of the bottle, and that the wire hangs in a bight between the neck of the bottle and the end of the shuttle. At this time the arms M , which embrace the bottle, are impelled to fly up on their shafts M' M' , as shown best in the top plan view, Fig. 13. The arms M M , as stated, 100 embrace the neck of the bottle and serve to hold the upper part of the bottle securely in position against the force of the wire-carrier and the other devices in the previous operations. The arms M are pivoted to shafts M' M' , and are turned upwardly thereon by means 105 which will be presently described. In their upward movement, as shown in Fig. 16, one of the arms on the side toward the wire-carrier collides with the bight of the wire, and, owing 110 to its peculiar shape and movement, catches the bight, and then shortly afterward the projecting end w of the strand of wire previously laid over the top of the cork, and carries them up over the top of the cork, impinging the 115 wires against the other arm M , thus holding both the bight and loose end vertically over the top of the cork, so that when the bottle is rotated the two parts of the wire are twisted together over the top of the cork, thereby 120 securing the cork in the bottle.

The mechanism for operating the arms M consists of the gears 32, which are mounted on the shafts M' M' , one of which being provided with the crank-lever M^2 , which is operated through the medium of the rod 33 by the eccentric-lever j^2 , which is provided with a friction-roller, j' , lying in the path of the cam j , rotating on the shaft F . 130

It will be observed upon reference to Fig. 16 that the cam j , rotating in the direction of the arrow, collides with the friction-roller j' , thereby retracting the rod 33, which actuates the crank M^2 , rotating its shaft M' , thereby

throwing up the arms M, which are geared together. While the arms are in the position illustrated in Fig. 16, compressing the bight and loose end of the wire together, the bottle-support J and bottle are rapidly rotated, thereby twisting the wire onto the cork and completing the operation of wiring the cork to the bottle, after which the cam k, having rotated so as to bring the notch 40 into coincidence with the stud 38 of the lever k', thereby again actuates the hammer N, which this time strikes the chisel-shaped projection n² on one of the jaws M, cutting off the wire between the jaws M M from the shuttle of the wire-carrier, completing the operation and leaving the bottle free to be removed from the machine.

The bottle is rotated as follows: The support J is mounted on the screw J', Fig. 16, and the screw J' has a gear or pinion, 44, which turns loosely thereon and is provided with an offset or shoulder, which, by means of the spring 60, is held normally in engagement with a clutch, 45, Fig. 2, formed on the collar J², which supports the lower end of the screw J'. It will be observed that the screw J' is journaled in suitable bearings in an upright on the machine, and that the screw-shaft J' is secured to the collar J² by means of a set-screw, 43. The screw J' serves, when the set-screw 43 is loosened, to adjust the bottle-support J to the desired height to bring the bottle in proper position to allow the plunger P to force the cork home flush with the mouth of the bottle. A rack, K, meshes with the pinion 44 and rotates the pinion when motion is communicated to the rack by the lever L, Fig. 2, by means of the cam j, which collides with a friction-roller, L', secured on a projection of the lever L. Motion is transmitted from the lever L to the rack by means of the connecting-rod L², Fig. 2. When the cam j impinges the friction-roller L', it forces the lever L toward the bottle, and the rack K rotates the pinion, which, as it turns, catches in the clutch 45 and revolves the bottle, thus twisting the wire, as described; and when the spring 49 returns the lever L to its normal position the rack K is retracted, and the pinion 44 is lifted out of the clutch 45, so that the bottle is not rotated in the reverse direction thereby. The pinion 44 is made light in weight, and a small space is left between the pinion and the bearing, so that the pinion may lift off of the clutch 45 in the return movement of the rack without rotating the bottle.

The operation of the lever L for rotating the bottle to twist the wire is timed with the movement of the cam k, so that the second stroke of the hammer N, which cuts off the wire, takes place at the time the bottle stops turning, and the arms M drop immediately thereafter, leaving the bottle free to be taken from the bottle-support J and replaced by another bottle to be operated upon.

The operation of my invention will be

readily understood from the foregoing and upon reference to the drawings.

It will be noticed upon reference to Fig. 2 7c that when the bottle is placed on the bottle-support J and motion communicated to the machine by depressing the pedal Q the wire-carrier and its shuttle are brought into operation and operate as hereinbefore described. 75 Simultaneous with the operation of the wire-carrier and its shuttle the compressor acts upon the cork which has been inserted therein, and the cam which actuates the plunger starts the plunger down and inserts the cork 80 about a quarter of an inch into the mouth of the bottle, where the further movement of the plunger is momentarily arrested. The rearward movement of the wire-carrier then commences, and simultaneously therewith the 85 first twisting of the wire takes place, leaving the wire on the cork. With the second forward movement of the carrier the cork is forced home by the plunger, and as the plunger is lifted out of the way the hammer N 90 lays the free end of the wire over the top of the cork. When the shuttle of the carrier comes over the neck of the bottle, the lowering of the carrier takes place, so as to bring the wire around the neck of the bottle, and 95 the second rearward movement of the carrier causes the wire to encircle the neck of the bottle and twists the wire the necessary length for the finishing steps. As the carrier comes forward the third time, thereby 100 slackening the wire into a bight, the arms M are raised up, carrying the bight of the wire and the free end together, and the bottle is revolved, as described, twisting the wire down onto the cork. At the completion of 105 the revolution of the bottle the hammer N make its second stroke and cuts off the wire clear of the shuttle, thereby leaving the bottle free, after the arms M fall, to be removed from the bottle-support J. The wire 110 is secured, as described, to the cork first and to the neck of the bottle, and finally the ends thereof twisted together, as described. When it is desired to remove the cork from the bottle, it is simply necessary to untwist the ends 115 of the wire, remove them from the top of the cork and the neck of the bottle, and again twist them together with the fingers, and by inserting a pencil or any other suitable implement in the bight a draw is produced wherewith the 120 cork may be readily drawn from the bottle without necessitating the use of a corkscrew or any other implement or breaking the neck of the bottle to remove the cork. The lower end of the bottle is held snugly to the bottle-support J by being forced into a rubber socket, r', secured inside of the circumferential flange projecting above the base of the bottle-support. It will also be noted that two strands 125 of wire are used in wiring the cork to the bottle, the said strands being led from the wire-reels r r and wound around the shuttle-jaws a a, as previously explained.

I do not restrict myself to the specific con-

struction and arrangement of the mechanism herein illustrated and described, since the same constitutes but one exemplification of my invention, and is designed to illustrate the 5 preferred example of my invention. Many of the parts are susceptible of modification in construction and arrangement without changing the principle of my invention.

Having thus fully described my invention, 10 what I claim as new, and desire to secure by Letters Patent, is—

1. The combination of a compressor for compressing the cork, a wire-carrier having jaws for applying the wire to the cork and bottle, 15 a plunger for forcing the cork into the bottle, and connected mechanism for actuating the several devices in their due order, substantially as and for the purpose set forth.

2. The combination of the compressor, plunger, wire-carrier having jaws, and hammer N, and connected mechanism for actuating the several devices in their due order, substantially as and for the purpose set forth.

3. The combination of the compressor, plunger, wire-carrier having jaws, bottle-support, and jaws M M, for grasping the neck of the bottle, and connected mechanism for actuating the several devices in their due order, substantially as and for the purpose set forth.

30 4. The combination of the plunger, wire-carrier and its jaws, jaws M M, for holding the two strands of wire together while the bottle is revolved to twist them onto the cork, the rotating bottle-support J, and connected mechanism for actuating the several devices in their due order, substantially as and for the purpose set forth.

5. The combination of the bottle-support, wire-carrier having jaws, jaws M M, and hammer N, for cutting off the wire after it has been twisted onto the cork, and connected mechanism for actuating the several devices in their due order, substantially as and for the purpose set forth.

45 6. The rotating wire-carrier I, having jaws a a, and shaft b, sliding endwise in the pivoted hanger U and oscillating on the hub U', journaled on the shaft F, substantially as and for the purpose set forth.

50 7. The wire-carrier I, provided with jaws a a, and shaft b, adapted to move endwise in a hanger, U, and to oscillate on the hub U', in combination with the elbow-bearing Z', the gears g g', and the pivoted actuating-shaft H, all substantially as and for the purpose set forth.

8. The wire-carrier I, having jaws a a, and shaft b, mounted in the hanger U to oscillate therewith, in combination with the cam h on 60 the shaft F and the pivoted lever V, substantially as and for the purpose set forth.

9. The hanger U, provided with the hub U', journaled on the shaft F, and the projecting bearing d', in combination with the rods f f', 65 sliding bearing d, carrying the shaft b of the wire-carrier, the cam i, for impelling the bear-

ing d and shaft forward, and the cord 3 and weight Y, for retracting it, substantially as and for the purpose set forth.

10. The combination of the wire-carrier I 70 and its jaws with the shaft b, elbow-bearing Z', gears g g', shaft H, sleeve o, slotted post X', swiveled bearing Z, gears G G', and collar H², setting in a cut-out in the bearing Z, for rotating the wire-carrier and permitting it 75 to oscillate, substantially as and for the purpose set forth.

11. The bottle-support J, having screw-shaft J', in combination with the collar J², pinion 44, clutch 45, and rack K, operated by rod L², 80 connected to lever L, actuated by cam j, substantially as and for the purpose set forth.

12. The combination, with the bottle-support J and its shaft J', of the loosely-mounted pinion 44, actuated by the forward movement 85 of the rack K to engage the clutch 45 and revolve the support J, and disengaged from the clutch by the rearward movement of the rack, substantially as and for the purpose set forth.

13. The compressor S', mounted movably in 90 the bracket-support S, composed of a semi-tubular section and a pivoted section, in combination with the rod s and its actuating-cam u, substantially as and for the purpose set forth.

14. The bracket-support S, provided with the curved slot or recess 29, in combination with the vertically-moving compressor S', hinged on pin 21 to the compressor-rod s and its actuating mechanism, substantially 100 as and for the purpose set forth.

15. The combination, with the bracket-support S, of the compressor S', having a hinged section or segment, the pivoted locking-lever K', having the projecting end 27 in the path 105 of the finger P', carried by the plunger P, and the finger P', substantially as and for the purpose set forth.

16. The combination, with the plunger P, of the vertically-movable compressor S', having 110 the bulb or swell 52 near its exit, substantially as and for the purpose set forth.

17. The combination, with the hammer N, having spring-shank N', secured to pinion N², of the rack N³, rod k², lever k', having stud 115 38, the cam k, having notches 39 and 40, and the spring 41, substantially as and for the purpose set forth.

18. The combination of the jaws M M, mounted on the shafts M' M', gears 32, crank 120 M², rod 33, eccentric-lever j², the cam j, for actuating the lever j², and a spring on the rod 33 for restoring the jaws M M to their normal position, substantially as and for the purpose set forth.

125 19. The combination of the wire-carrier I, having jaws, the main shaft C, and intermediate mechanism for operating the jaws, with the gear G, having notches 14, the lever H², having pawl-hook 15, a clutch, p', and the 130 pivoted lever F', carried by the sliding section of the clutch p', to force the pawl of lever

H' from engaging the notches in gear G, and the spring 51, for forcing the lever H' toward the gear for stopping the wire-carrier in its normal position after twisting the wire, substantially as and for the purpose set forth.

5 In testimony whereof I have hereunto signed my name, in the presence of two attesting

witnesses, at Syracuse, in the county of Onondaga, in the State of New York, this 18th day of July, 1888.

HENRY LA CASSE.
